**RIGIDIFIED MULTI-OPENING APERTURE
CARDS**

Robert Beispeil, Des Plaines, Ill., assignor to Microseal Corporation, Chicago, Ill., a corporation of Illinois
Filed Apr. 22, 1964, Ser. No. 361,824
7 Claims. (Cl. 40—159)

This invention is generally related to film record cards and a film record card tool and is more particularly directed to an improved film record card having a plurality of apertures wherein microfilm strips and the like may be mounted and an improved tool therefor.

With the ever increasing use of microfilm records, it has been desirable to provide a film record card that may contain all the statistical information or a major portion thereof on microfilm and one which has sufficient microfilm mounting means to allow periodic additions of microfilm to the card.

Film record cards are generally used in very large quantities running often into the many thousands. The cards generally have indicia of one sort or another formed in or over all or a portion of one or both sides of the card. The indicia may comprise a series of punched holes or a series of magnetic ink impressions and the like as will be familiar to those skilled in the art. The cards are generally vertically stacked and compressed against one another. Each card is then individually slid vertically with respect to the stack and sorted in this manner. Such sorting machines are almost universally adapted to pass the record cards therethrough in a sideways manner as opposed to an endwise manner. Sensing fingers are generally employed in the sorting machines and there is relative movement between these fingers and the cards from one side of each card to the other as it passes through the machine.

The present action of the sorting machine and the sensing fingers present problems in the construction and design of film record cards. Film record cards heretofore revised have caused considerable jamming in record cards sorting machines with the result that the sorting machines have had to be operated at very slow speeds or frequently stopped to unjam them. The jamming of the sorting machines is brought about by vertical collapse of the film record card and also by adjacent film record cards having their empty microfilm pocket windows pressed into the empty pocket windows of the card being sorted which prevents vertical sliding of the card. This hindrance to vertical sliding of adjacent cards is especially acute in multi-aperture cards where some of the apertures or pockets are completely empty.

The present invention has obviated these problems of film record cards in jamming the sorting machine by providing each film record card aperture or pocket with at least one non-jamming or reinforcing rib to prevent adjacent cards with empty pockets from hindering the card from being vertically sorted.

Further, the present invention provides an unique non-jamming rib remover tool in order to remove the non-jamming ribs when it is desired to insert additional microfilm in the film record card aperture or pocket.

Therefore, it is an object of the present invention to provide an improved multi-aperture film record card.

It is another object of the present invention to provide an improved multi-aperture film record card having means to prevent jamming of said cards in sorting machines.

It is still another object of the present invention to provide a multi-aperture film record card wherein each aperture has at least one non-jamming means therein to both reinforce the card and prevent jamming thereof in sorting machines.

2

It is still further another object of the present invention to provide a multi-aperture film record card wherein each aperture contains at least one integral non-jamming reinforcing rib.

It is further another object of the present invention to provide an improved tool for removing a non-jamming rib from the aperture of a film record card.

Other objects, features, and advantages of the present invention will become apparent to those skilled in the art after a careful consideration of the following disclosure and drawing wherein like reference numerals refer to like and corresponding parts.

On the drawings:

FIGURE 1 is an elevational view illustrating a multi-aperture film record card constructed in accordance with the principles of the present invention;

FIGURE 2 is a partial elevational view illustrating a removing tool constructed in accordance with the principles of the present invention in the process of removing a non-jamming reinforcing rib from the film record card illustrated in FIGURE 1; and

FIGURE 3 is a partial longitudinal cross-sectional view taken along lines III—III of FIGURE 2.

As shown on the drawings:

Referring to FIGURE 1 there is illustrated a fenestrated film record card 11 comprising the usual card 12 having three rectangular apertures 13, 14 and 15.

Each aperture has its axis extending substantially parallel to the length of the card 12 and extending for a major portion of the card length. The thickness of each aperture is predetermined to effectively mount a piece of microfilm such as 16 and 17 therein. Each aperture has a top wall 18 and a bottom wall 19 and the apertures 13, 14 and 15 are parallel and spaced a predetermined distance apart. Each aperture 13, 14 and 15 is provided with respective non-jamming reinforcing ribs 20, 21 and 22 respectively. The reinforcing ribs 20, 21 and 22 are preferably integral with the card 12 and extend perpendicular to the top and bottom walls 18 and 19 of the apertures. The rib 21 is preferably offset from the ribs 20 and 22 as is illustrated in FIGURE 1, so as to give additional vertical strength of the fenestrated card 11. It is of course understood that the ribs 20, 21 and 22 have a thickness substantially less than the width of their corresponding apertures and also that said ribs may be angularly displaced and still perform their non-jamming function. However, angularly displaced ribs would not appreciably reinforce the apertured card 12. Further, the ribs must be thin enough to allow their removal without leaving detrimental ragged edges on the top and bottom walls of the apertures and also without ripping the card 12.

It is of course understood that the reinforcing and non-jamming function of the ribs 20, 21 and 22 will be performed if all the ribs are vertically aligned.

Referring to FIGURES 1 and 3, transparent enveloping sheets 13 and 14, rectangular in configuration, are mounted on the front and rear surfaces respectively of the card 12 so that they overlie the apertures 13, 14 and 15. The enveloping members 13 and 14 are mounted over the apertures so that their edges overlie portions of the card defining the apertures (that is, the edge of each sheet does not terminate at the edge of the apertures) but only three edges 25, 26 and 27 of each of the enveloping members and also, the portions 29 and 30 between the apertures are secured to the respective surfaces of the card by suitable adhesive 28. In each case, the overlying edge 31 has an unsecured portion 32 adjacent one end of the apertures and being at least equal to the width of the apertures. Since the unsecured portions 32 are affixed to the card 12 only at their ends a slight gap 33 may be formed between the enveloping members and the

record card. This gap would be very small and in fact, may not exist at all. This of course would be dependent upon the manner in which the enveloping members were mounted on the card 12 and on whether or not the card 12 is disposed in a completely flat plane.

Generally speaking, it would be understood that a film strip 16 may be inserted through the gap 33 into the film aperture or pocket 19 formed intermediate the enveloping members 23 and 24 and that once disposed within the pocket, as illustrated in FIGURE 1, it would be protected substantially from all atmospheric impurities as well as from stains caused by handling and the like. Since the enveloping members 23 and 24 are transparent, light may be transmitted through the enveloping members as well as the film 16 if it is desired to project the film image on a screen and thus removal of the film for this purpose is not necessitated. Still further, deleterious particles will be prevented from entering the pockets or apertures 13, 14 and 15 since the edge portions of the enveloping members which are not secured to the card 12 substantially overlie the card and are normally maintained in juxtaposition with the respective surfaces of the card due to the fact that they are maintained relatively taut by the other secured edges thereof.

The enveloping sheets 23 and 24 illustrated are sheets of polyethylene terephthalate. However, any of the well known film record card enveloping sheet material may be used. Film record cards of the multi-aperture type are utilized to hold microfilm such as microfilm 16 and 17. These record cards are utilized for progressively adding information thereto as the information is gathered. Therefore, in a sorting machine where there are thousands of cards vertically stacked against each other some of the cards have only a small portion of the pockets containing a microfilm and adjacent cards have some of their pockets completely empty. Where adjacent cards have empty film pockets there is presented a problem of jamming the sorting machine. The sorting machine has all the film record cards vertically stacked and a great deal of pressure is exerted on the cards. The machine is operated to move the cards perpendicular to their vertical axis and the cards are sorted individually and vertically relative to each other. Since the enveloping sheets 23 and 24 have a combined thickness of a mil or less and the tabulator card has a thickness of about 7.4 mils, the compression of the adjacent cards would cause the enveloping sheets 23 and 24 to be compressed when the card is being vertically moved relative to the stack of cards and the film pocket is empty. A film record card not having the reinforcing ribs 20, 21 and 22 and having cards with adjacent empty pockets, would cause the top wall 18 of the empty pocket of the card being sorted to abut against the bottom wall 19 of the empty pocket in the adjacent card in the sorting stack. This abutment causes the machine to jam. However, by utilizing the cards of the present invention, having the non-jamming reinforcing ribs 20, 21 and 22, the cards are prevented from forming the abutting jamming relationship between film record cards wherein adjacent film record cards both having empty film pockets.

Referring to FIGURES 2 and 3 there is illustrated a non-jamming rib remover tool 41 having an elongated flat rectangular handle 42 and a half arrow head 43. The head 43 has a rounded end 44 with sides 45 diverging towards the handle 42 and a top surface 46 inclining from the rounded end 44 towards the handle 42 to a rounded inner end 47 and a front inner wall 48 extending vertically and integrally with the handle 42. The front wall has formed therein a slot 49 extending the width of the head. The slot has a thickness of approximately equal to the thickness of the rib 21 and extends inwardly into the head 70 from the front wall 48 at an acute angle to the handle.

Therefore, when it is desired to add additional microfilm besides the film 17 to the pocket 14 the microfilm 17 is removed and the removing tool 41 placed in operation. The tool head is inserted between the gap 33 75

formed by the sheet 24 on the undersurface of the card 12. The head front wall 48 is slid beyond the rib 21. Then the tool is removed in the pocket so that the wall 48 moves towards the rib 21. The rib is engaged by the slot 49. The angle or configuration of the slot is such that it turns the rib in a clockwise direction, as is illustrated in FIGURE 3. Therefore, the horizontal movement of the tool subjects the rib 21 to both turning and horizontal forces which allow it to be separated from the top and bottom walls of the pocket 14 and leave clean edges behind. It is important to the removal feature of the present invention that there be no adhesive between the non-jamming ribs 20, 21 and 22 and the overlying sheets 23 and 24 because such adhesive would hinder the proper removal of the non-jamming ribs.

The removing tool has a width less than the width of the film pockets and has a thickness which is calibrated such that it will not separate the glued portions of the sheets 23 and 24 from the card 12. The removal tool is shown as being made from metal but it is of course understood that the tool may be made from any desired material such as any of the well known plastic used to make solid objects.

Although the present invention has been described as utilizing integral non-jamming ribs it is of course understood that the ribs need not be integral with the card 12 but may be separate ribs releasably secured to the cards such as by non-permanent adhesives or other suitable fastening means.

Therefore, it is seen where I have provided the film record card industry with a rigidified non-jamming multi-opening apertured card which will not jam the film record card sorting machines when said cards are vertically sorted.

It will be understood that a film record card constructed in accordance with the principles of my invention will have a wide variety of uses but it should be kept in mind that the illustrated embodiments of my invention have been used for illustrative purposes only and that various modifications and variations in the invention may be effected without departing from the spirit and scope of the novel concepts thereof.

I claim as my invention:

1. In a film record card having a plurality of longitudinally extending and spaced parallel apertures formed therein with a transparent sheet overlying both sides of said apertures and having three edges and the lands between the apertures adhesively secured to the sheets, at least one removable non-jamming rib being integral

45 with and interconnecting the top and bottom walls of each pocket to reinforce said card and substantially prevent the card from jamming in a vertical sorting machine, and

50 said non-jamming ribs having a relatively thin width such that they may be cleanly removed from the pockets.

2. A film card non-jamming rib removing tool comprising:

an elongated handle,

55 a half arrow head formed at one end of said handle, and

said half arrow head having a non-jamming rib engaging groove in the inner face thereof to engage and remove said rib.

3. A film card non-jamming rib removing tool comprising:

an elongated rectangular handle, a half arrow head formed at one end of said handle, said half arrow head having a wall extending upwardly from the handle,

said upwardly extending wall having a rib engaging groove formed therein and extending the width of said half arrow head, and

said groove having an axial center line forming an acute angle with said handle

whereby said tool is adapted to exert a turning and horizontal force on a non-jamming rib when said rib is engaged by said head groove.

4. A film card non-jamming rib removing tool comprising:

an elongated rectangular handle,
an enlarged head portion formed at one end of said handle,
said enlarged head portion having a wall extending upwardly from the handle,
said upwardly extending wall having a rib engaging groove formed therein and extending the width of said head portion, and
said groove having an axial center line forming an acute angle with said handle

15 whereby said tool is adapted to exert a turning and horizontal force on a non-jamming rib when said rib is engaged by said head groove.

5. A film record card comprising:

a comparatively rigid supporting frame having a film 20 opening formed therein,
transparent comparatively non-rigid sheet material overlying both sides of said supporting frame and forming a film pocket thereby,
said transparent comparatively non-rigid sheet being 25 adhesively secured to said supporting frame adjacent said opening,
a transverse rib extending across the film opening and being joined to the supporting frame at opposite edges of the opening and being non-adhesively associated with said transparent comparatively non-rigid sheet,
30 whereby said transverse rib may be easily removed from said film pocket.

6. A film record card comprising:
a comparatively rigid supporting frame having a film opening formed therein,
transparent comparatively non-rigid sheet material overlying both sides of said supporting frame and forming a film pocket thereby, and
temporary rigidifying means removably disposed in said film pocket and giving vertical rigidity to said supporting frame thereby.

7. A film card non-jamming rib removing card tool comprising:

an elongated handle,
a half arrow head formed at one end of said handle, said half arrow head having a wall extending upwardly from the handle,
said upwardly extending wall having a rib engaging groove formed therein, and
said groove forming an acute angle with said handle.
